UNITED STATES PATENT OFFICE.

EDWARD F. VANDERBOSCH, OF LAPORTE, INDIANA.

OSCILLATING MECHANISM FOR WASHING MACHINES.

Application filed December 17, 1923. Serial No. 681,277.

To all whom it may concern:

Be it known that I, EDWARD F. VANDERBOSCH, a citizen of the United States, residing at Laporte, in the county of La Porte and State of Indiana, have invented certain new and useful Improvements in Oscillating Mechanism for Washing Machines, of which the following is a specification.

The invention relates to oscillating mechanism for washing machines, and has for its object to provide a device of this character wherein a pivoted washing machine receptacle will be operated in a manner whereby jerking or hammering of the parts at the time of reversal of movement of the receptacle will be obviated.

A further object is to provide oscillating mechanism for washing machine receptacles, which mechanism comprises a slidable cross-head mounted in guides of one end of the receptacle, and provided with an internal gear driven by drive pinions at a fixed point for reciprocating the cross head in the guides and imparting an oscillatory movement to the receptacle. Also to provide an idle gear carried by the cross head and with which idle gear the drive pinion meshes for holding the drive pinion in mesh with the internal gear during the reciprocation of the cross head by the drive pinion. The idle gear also acts as a thrust bearing for the drive pinion.

A further object is to slidably mount the cross head radially to the axis of the receptacle, thereby insuring oscillations of equal length to either side of the axis of the receptacle.

A further object is to provide a motor for driving the drive pinion through the medium of a worm and worm gear carried by the frame of the washing machine adjacent the crosshead, thereby providing a compact structure.

A further object is to provide an oscillating mechanism for a washing machine receptacle wherein the pivoted receptacle is oscillated through the reciprocation of a radially movable crosshead, mounted in guides.

With the above and other objects in view the invention resides in the combination and arrangement of parts as hereinafter set forth, shown in the drawing, described and claimed, it being understood that changes in the precise embodiment of the invention may be made within the scope of what is

claimed without departing from the spirit of the invention.

In the drawing:—

Figure 1 is a perspective view of a washing machine, showing the device applied thereto. 60

Figure 2 is a front elevation of one end of the washing machine receptacle, showing the oscillating mechanism applied thereto. 65

Figure 3 is an enlarged side elevation of one end of the washing machine receptacle, showing the oscillating mechanism applied thereto.

Figure 4 is a horizontal sectional view 70 through one end of the receptacle, taken on line 4—4 of Figure 3.

Referring to the drawing, the numeral 1 designates the frame of the washing machine and 2 the receptacle thereof, in which 75 receptacle, articles of clothing are placed during a washing operation. In washing machines of the oscillating type, as at present constructed, when the direction of oscillation is reversed, a jerking or hammering of the parts takes place incident to the sudden reversal. To obviate this difficulty the receptacle 2 is oscillated on its pintles 3 by means of a crosshead 4, which cross-

head is slidably mounted in crosshead guides 5 disposed within a casing 6 secured by means of rivets 7 to one end of the receptacle 2. The crosshead 4 is radially movable in relation to the pintles 3 of the receptacle, thereby insuring the same length of 80 oscillatory strokes to each side of the vertical longitudinal center of the receptacle 2, consequently a uniform agitation will take place within the receptacle 2 during the operation of the device. Crosshead 4 is pro-

vided with an internal gear 8, with which gear a fixed drive pinion 9 meshes, which pinion is carried by a horizontally disposed shaft 10, which is rotatably mounted in a bearing 11 of the outwardly extending portion 12 of a gear casing 13. Disposed on the upper end of the gear casing 13 is a conventional form of motor 14, preferably 90

an electric motor, which motor has its drive shaft 15 vertically disposed and provided 95 with a worm 16, which meshes with a worm gear 17, therefore it will be seen that the drive pinion 9 is driven by the motor 14, and said drive pinion will be constantly rotated in one direction by the motor during 100

the operation of the motor, but will remain at a fixed point, as the same is supported 110

by the portion 12 of the casing 13 of the frame 1. During the rotation of the drive pinion 9, the crosshead 4 is moved towards the axis of the receptacle 2, and at the same time gradually moved to one side of the longitudinal vertical center of the receptacle, thereby swinging the receptacle on its pintles 3 to the dotted line position shown in Figure 3, at which time the drive pinion 9 assumes a dead center position gradually, consequently jerking or hammering of the parts is obviated, as there is momentarily no sliding movement of the crosshead 4 when it assumes the dead center position as shown in dotted lines in Figure 3. However as the pinion 9 continues to rotate and reverses the movement of the crosshead from the dotted line position shown in Figure 3, the receptacle 2 is swung in the opposite direction gradually until the drive pinion 9 reaches the opposite side of the internal gear 8, at which time the drive pinion and crosshead are again at a dead center position, and the direction of swing of the receptacle is reversed. The above operation continues, which operation comprises a reciprocation of the crosshead 4 and a simultaneous oscillation thereof.

Secured to the crosshead 4 is a spider 17, which spider is provided with a stub shaft 18, axially disposed in relation to the internal gear 8, and on which stub shaft is rotatably mounted an idle gear 19. The idle gear 19 moves with the crosshead 4, and meshes with the drive pinion 9, consequently not only acts as a thrust bearing for the drive pinion 9, but at the same time maintains the drive pinion 9 in mesh with the internal gear as the drive pinion 9 moves around the internal gear 8, thereby insuring a positive operation of the device and the reciprocation and oscillation of the crosshead 4 during the rotation of the drive pinion 9.

From the above it will be seen that a driving mechanism is provided for oscillating washing machine receptacles wherein the structure is compact, and the receptacle oscillated by the reciprocation of a crosshead in guides, which crosshead is simultaneously oscillated. It will also be seen that the crosshead is driven by a drive pinion disposed at a fixed point, and meshing with an internal gear carried by the crosshead, thereby getting a maximum oscillation in a minimum amount of movement of the crosshead.

The pintle 3 of the receptacle 2, which is disposed adjacent the driving mechanism may be mounted in any manner desired, however it is preferably carried by a bar 20, which connects the outer sides of the guides 5, thereby allowing the crosshead 4 to move between the pintle 3 and the adjacent end of the receptacle 2 behind the bar 20, therefore it will be seen that the crosshead will not

come into engagement with the pintle 3 in its upward movement, and the driving mechanism may be placed relatively close to the axis of the receptacle 2.

The invention having been set forth what is claimed as new and useful is:—

1. The combination with a pivoted receptacle, of means for oscillating said receptacle, said means comprising a crosshead, guides for said crosshead carried by the receptacle, means for simultaneously reciprocating and oscillating the crosshead comprising a gear carried by the crosshead, a drive pinion meshing with the crosshead gear, and means for rotating the drive pinion.

2. The combination with a pivoted receptacle, of means for oscillating said receptacle, said means comprising a crosshead, guides for said crosshead carried by the receptacle, means for simultaneously reciprocating and oscillating the crosshead, said means comprising a gear carried by the crosshead, a fixed rotatable gear meshing with the crosshead gear, and means for rotating the fixed rotatable gear.

3. The combination with a pivoted receptacle, of means for oscillating said receptacle, said means comprising a movable crosshead, guides carried by the receptacle in which said crosshead is slidably mounted, an internal gear carried by the crosshead, a fixed drive pinion meshing with the internal gear, means cooperating with the drive pinion for maintaining the same in mesh with the internal gear, and means for rotating the drive pinion.

4. The combination with a pivoted receptacle, of means for oscillating said receptacle, said means comprising a movable crosshead guides carried by the receptacle in which the crosshead is mounted, an internal gear carried by the crosshead, a fixed rotatable drive pinion meshing with the internal gear, an idle pinion carried by the crosshead and meshing with the drive pinion, said idle pinion forming means for maintaining the drive pinion in mesh with the internal gear during the rotation of the drive pinion.

5. The combination with a pivoted receptacle, of means for oscillating said receptacle, said means comprising a movable crosshead, said crosshead being mounted and guided in guide members carried by the receptacle, a gear carried by the crosshead, a drive pinion meshing with said gear, means for maintaining the drive pinion in mesh with the crosshead gear, said drive pinion being fixed as to position and forming means whereby when rotated the crosshead will be reciprocated in the guides and simultaneously oscillated.

6. The combination with a pivoted receptacle, pintles carried by said receptacle, supporting bearing members for said pintles,

one of said pintles being spaced from the end wall of the receptacle, of a gear driven reciprocated and oscillated crosshead for oscillating said receptacle, said crosshead being mounted in guides carried by the end wall of the receptacle and movable between the spaced pindle and the end wall of the receptacle.

7. The combination with a pivoted receptacle, pintles carried by the end walls of

said receptacle, supporting bearing members for said pintles, of a gear driven reciprocated and oscillated crosshead for oscillating said receptacle, and guides for said crosshead carried by an end wall of the receptacle whereby the crosshead is movable between said end wall and the member supporting the pindle of said end wall.

In testimony whereof I affix my signature.
EDWARD F. VANDERBOSCH.
